UNITED STATES PATENT OFFICE

157,927

BOTTLE CAP REMOVER

Ralph Van Trine, Durham, N. C., assignor of 30
per cent to Leona T. Van Trine and 30 per cent
to Marian Van Trine Davis, Durham, N. C.

Application September 30, 1948, Serial No. 148,892

Term of patent 14 years

(Cl. D44—29)

To all whom it may concern:

Be it known that I, Ralph Van Trine, a citizen of the United States, residing at Durham, in the county of Durham and State of North Carolina, have invented a new, original, and ornamental Design for a Bottle Cap Remover, of which the following is a specification, reference being had to the accompanying drawing, forming part thereof.

Figure 1 is a front elevational view of a bottle cap remover, showing my new design;

Figure 2 is an edge view of same;

Figure 3 is a top plan based on Figures 1 and 2.

I claim:

The ornamental design for a bottle cap remover, as shown.

RALPH VAN TRINE.
